UNITED STATES PATENT OFFICE

2,244,189

THERMOSTATICALLY CONTROLLED GRATE

James K. Dukas, Kingston, Pa.

Application November 8, 1939, Serial No. 303,488

1 Claim. (Cl. 126—169)

This invention relates to thermostatically controlled grates and has for one of its objects the production of a simple and efficient means for automatically discontinuing the operation of a furnace grate before the hot coals in the fire-box reach the grate and fall into the ash-pit.

A further object of this invention is the production of a simple and efficient means placed within the fire-box for contact with the hot coals within the fire-box at a selected position above the grate for automatically shutting-off the operation of the grate when the hot coals contact said means.

Other objects and advantages of the present invention will appear throughout the following specification and claim.

In the drawing:

Figure 1 is a side elevational view of a furnace, certain parts being shown in section and illustrating the position of the heat conducting bar;

Figure 2 is a top plan view of a furnace, certain parts being shown in section and illustrating the position of the heat conducting bar;

Figure 3 is a vertical sectional view taken on line 3—3 of Figure 1;

Figure 4 is a perspective view of the heat conducting bar and heavy duty thermostat; and

Figure 5 is a diagrammatic view of a modified form of the invention.

By referring to the drawing, it will be seen that 10 designates the conventional type of furnace having an automatically operated grate 11 similar to that shown in my previous patent relating to furnace grates, Number 2,184,292, issued December 26, 1939. It has been found by practical experience that automatically operated grates tend to bring down the ashes to a point where the hot coals directly contact the grates and fall into the ash-pit thereby tending to burn out these grates. To avoid this difficulty, I have discovered that by placing a heat conducting bar 12 within the fire-box in the manner shown in the drawing, this difficulty may be overcome. This heat conducting bar 12 is preferably placed at a safety zone of approximately 1½ inches above the grate 11 in the ash-bed or fire-box and below the active fire, in the position shown in Figure 1.

The heat conducting bar 12 is preferably one-half inch thick and 1½ inches wide, the narrow edge being uppermost in the manner illustrated in Figure 3. The bar 12 is placed transversely within the ash-bed or fire-box and one end indicated by the numeral 13 projects beyond the cas-

ing of the furnace and supports a heavy duty thermostat control 14 at its outer end, which thermostat control is connected to the wires 15 and 16 which control the grate operating mechanism 17 similar to that described in my previous patent above identified. The heavy duty thermostat which is preferably used registers and operates up to 200° of heat or over. The melting point of iron and other similar metals is over 400°. When the mechanical grates 11 start to operate and reduce the ash-bed, the fire within the fire-box comes into contact with the iron heat conducting bar 12, which bar becomes hot and the heat is transmitted to the outer end 13 of the bar where the thermostat is mounted and set so as to throw off the power through the lines 15 and 16 at a temperature of approximately 100° or 150°.

The conventional blower usually employed in connection with an apparatus of this character works independently from this ash-removing mechanism, and is operated by the ordinary temperature thermostat which registers only up to 80° or 100°, and is located in a room in the building which is heated by the furnace. When the temperature in the room drops, this thermostat starts the blower. However, as the coal is consumed within the furnace and the ashes are accumulated in the fire-chamber, the heat conducting bar 12 which carries the heavy duty thermostat 14 becomes cold and throws on the power of the mechanical grate shaker. The mechanical grate then starts and reduces the ashes until the fire comes into contact with the bar 12 again and the heat absorbed by the bar 12 and passing to the thermostat 14 works the thermostat 14 to operate and throw off the power which controls the operation of the grate.

The present device is particularly adapted in connection with ash-removing devices where an overhead feed is employed for feeding fuel to the furnace and it has been found that the present heat conducting bar and the location thereof in the furnace will provide an efficient means in conjunction with the thermostat 14 for automatically cutting off the power which operates the grates 11 when the hot coals are brought down within a predetermined distance with respect to the grate, thereby preventing the hot coals from being deposited in the ash-pit.

It should be understood that the present invention relates solely to the location of the heat conducting bar within the furnace and its relationship to the grates as well as the thermostat 14 which controls the cutting off of the power

whereby the operation of the grates will be discontinued when the hot coals are brought within a predetermined distance of the grate. Any suitable mechanism may be employed for controlling and actuating the conventional blower, not shown, but ordinarily used in furnaces of this character, but the present invention relates solely to the means for cutting off the power from the grate-actuating mechanism at a predetermined time.

By carefully considering Figure 4, it will be seen that a heavy duty surface thermostat 14 is carried directly by the end of the bar 12 which projects beyond the furnace. The thermostat 14 shown is of the conventional type and is only an example of those suitable for use in the present instance. The surface aquastat illustrated in the catalog of W. W. Grainger, Inc., Net Price Motor Book No. 114, on page 59, printed in July of 1939, although designed to be responsive to water temperatures, may be used to advantage if desired, since the temperature of the bar will efficiently actuate this type of aquastat.

In carrying out the invention, one type of arrangement may be employed such as that illustrated in Figure 1, wherein the thermostat or aquastat 14 has one side directly connected to the main power line 18 through the medium of the wire 15 and the other side of the aquastat or thermostat 14 is directly connected to the motor 19 which drives the grate-actuating mechanism 17. The other side of this motor 19 is electrically connected to a wire 20 leading to the pressure control and room thermostat which also leads to the power line 22. A motor 23 which actuates a blower 24 is also electrically connected to the wires 18 and 20, as shown in Figure 1.

In Figure 5, I have shown a modified form of the invention illustrating the manner in which my device may be applied to the traveling grate type of grate wherein the traveling grate is indicated by the numeral 25, to which fuel is fed from a hopper 26, the grate 25 depositing ashes

into an ashpit 27 at the opposite end of the grate 25. A head conducting bar 12^a similar to the bar 12 extends transversely across the discharge end of the traveling grate 25 and to this bar 12^a is secured a heavy duty thermostat 14^a, similar to that as illustrated in Figure 4. This thermostat 14^a is electrically connected to a motor 19^a similar to the motor 19 which drives the traveling grate 25.

10 It should be understood that this device may be applied to any type of grate where the fuel is fed thereto from above, and I do not desire to limit myself to the use of this heat conducting bar and heavy duty thermostat in conjunction with any particular type of grate.

15 Certain detail changes in the mechanical construction and arrangement of parts may be employed without departing from the spirit of the invention, so long as such changes fall within the scope of the appended claim.

20 Having described the invention, what is claimed as new is:

25 In combination with a furnace, a grate, a heat conducting bar mounted within the fire-box and above the grate, said heat conducting bar having a projecting end extending outside and beyond the outer wall of the furnace, a mechanical grate shaker, a thermostat carried by the projecting end of said heat conducting bar at a point 30 outside of the furnace, and means electrically connecting the mechanical grate shaker with the thermostat for controlling the operation of the mechanical grate shaker, the heat from the furnace being adapted to travel longitudinally of the heat conducting bar toward the projecting end 35 thereof for actuating the thermostat in a manner whereby the mechanical grate shaker will be rendered inactive when the temperature of the bar reaches a predetermined degree to cause the thermostat to automatically cut-off the current from the mechanical grate shaker and render the mechanical grate shaker inactive.

40 JAMES K. DUKAS.
